UNITED STATES PATENT OFFICE.

WILLIS A. SCHLEIT, OF SYRACUSE, NEW YORK.

BROODER.

1,245,041.

Specification of Letters Patent. Patented Oct. 30, 1917.

Application filed October 6, 1914. Serial No. 865,814.

To all whom it may concern:

Be it known that I, WILLIS A. SCHLEIT, a citizen of the United States, and resident of Syracuse, in the county of Onondaga, in the State of New York, have invented new and useful Improvements in Brooders, of which the following, taken in connection with the accompanying drawings, is a full, clear, and exact description.

10 This invention relates to certain improvements in brooders for fowls, such as chickens and the like, and more particularly to a brooder for installation in colony houses in which young chickens are reared for the first few weeks or months after hatching.

Brooders of this character involve the use of a heating means and a hover forming an inclosed space for the little chickens and adapted to be heated by said means.

20 The primary object of the invention is to provide a structure by means of which heat is economically and efficiently diffused over the backs of the fowls within the hover.

Another object is to provide means for 25 automatically regulating the temperature of the hover at any predetermined point.

A further object is to provide ventilating means for the hover, operating in connection with the temperature regulating 30 means.

A further object is to provide the hover with a movable sector shaped section, rendering the heater accessible for coaling, firing and cleaning.

35 The floor of colony houses for young chickens is usually covered with litter of highly inflammable character, rendering the use of ordinary combustion heaters dangerous, due to the dropping of hot coals, 40 ashes, sparks, etc., particularly during the shaking of the stove to remove ashes, clinkers, etc., and a further object of this invention, therefore, relates to the provision of means for entirely eliminating this danger 45 by providing the heater with a sealed base preventing ashes or coals from falling outside.

Other objects will appear from the following description, taken in connection with 50 the accompanying drawings, in which—

Figure 1 is a perspective view of the brooder, showing the movable sector shaped section as swung over the main body of the hover to allow free access to the heater.

55 Fig. 2 is a view, largely in section, of the

temperature controlling means and the upper portion of the heater.

Fig. 3 is a vertical cross section diametrically of the brooder, a portion of the hover being broken away.

Fig. 4 is a horizontal cross section through the heater looking down upon the grate.

The invention comprises a heater —1— having an outwardly curved upper portion —2— to deflect the heated air outwardly, 65 and a solid bottom —3— having cross ribs —4— upon which a suitable ash-pan —5— rests.

The bottom wall —3— is spaced a suitable distance from the floor upon which the 70 heater is adapted to rest, by means of a base —6—, to prevent heating of the floor. This heater may be provided with any suitable form of grate, as the grate —7— illustrated herewith and commonly known as a 75 sliding, slicing grate, formed of a stationary section —8— having a series of lugs —9— engaged with slots in the walls of the heater, and a movable section —10— rotatable thereon.

The front wall of the heater is provided with a slot or opening —11—, and the movable section —10— of the grate is provided with a projecting member —12— preferably formed integral therewith and having 85 a lug —13— positioned in the slot —11— and provided with an opening —14— for the reception of a shaking-rod, not illustrated. The member —12— is of sufficient width and thickness to entirely cover the 90 slot —11— in any position of the grate as limited by the contact of the lug —13— with the opposite ends of the slots —11—, and readily slides against the inner side of the wall of the heater to allow the section —10— 95 to be rotated upon the section —8—. By this construction the heater is easily and readily shaken and the danger of ashes and coals dropping outside the heater through the slot in which the shaker moves is eliminated.

The ash-door —15— is readily accessible from the front of the heater and extends out substantially square in front of the heater, thereby allowing the heater to accommodate a larger ash-pan with a less length of ash-door.

The heater is preferably provided with a coal feed magazine —16— extending some distance above the heater and above the 110

hover hereinafter described, and likewise projecting some distance downwardly into the fire-pot, and this magazine is preferably provided with a removable closure

5 —17—.

10 A series of posts —18— as shown, four in number, are mounted upon the top of the heater, preferably removably mounted by means of suitable bolts, and may be of any suitable or desired length adapted to receive and support a suitable hover —19— formed of a top portion —20— preferably horizontally disposed and circular in shape, and having a vertically depending flange —21—

15 of any suitable width and adapted to position and support a side wall, hereinafter described, operating in conjunction with the outwardly curved upper portion of the heater to deflect the heated air across the hover and downwardly along its edge.

20 For the purpose of suitably connecting this hover to the posts —18—, a pair of transverse crossing bars —22— and —23—, U-shape in cross section, extending substantially diametrically of the portion —20— of the hover, and at substantially right angles to each other and having their opposite ends bent at substantially right angles to their main body to support a side wall —24— in contact with and forming a substantial continuation of the flange —21—, are provided and are suitably connected to the portions —20— and —22— by means of rivets or bolts —25—.

25 The posts —18— are seated in the channel of the U-shaped bars, and the bars and the portion —20— are connected to the posts by means of bolts —26— having a threaded seat in

30 relation with an internally threaded seat in the upper end of each of the posts —18—. The side wall —24— is provided with a depending curtain —27— of felt or similar material adapted to retain the heat within the hover and prevent heating up of the

35 room surrounding the hover.

40 The hover is provided with a movable section —28— adapted to form a substantial continuation of the remainder of the hover so far as form and outline are concerned, and is hinged to the heater by means of a suitable hinging member —29— connected to the horizontally disposed portion of the section —28— and to one end of a lifting arm —30—, the other end of which is attached to the section —28—. The hinging member —29— is rotatably mounted upon the pivots —31— and —32— so that the section —28— may be moved around and outside of the main body of the hover, and

45 by reason of the fact that this section is hinged eccentrically to the circular top portion —20—, the pivot —32— is offset to one side of the axis of the pivot —31—, and is disposed a short distance farther from the magazine feed —17— than is the pivot

—31—, so as to tilt the movable section relatively to the main body of the hover as it is moved to open position, thereby enlarging the possible width of the movable section consistent with operation.

70

As shown, this movable section is sector shaped and comprises about one-fourth of the circumference and extent of the hover and moves outside the main body of the hover so as not to disturb or frighten the 75 fowls, and allows free access to the heater and to the temperature controlling means hereinafter described.

The heater is provided with a chamber —33— having communication with the fire-box through an opening —34— and with a smoke pipe —35— through an opening —36—, and with the interior of the hover through an opening —37—. The opening —34— is provided with a suitable movable 80 closure or valve —38— adapted to be operated, through suitable connections as the pivoted arm —39— and link —40—, by a thermostatic device comprising a bellows —41— adapted to expand under heat and 85 operating upon a pivoted arm —42— connected to an upright rod —43— by means of a spring —44—, which rod operates upon the pivoted arm —39— to close the valve —38— against the action of an adjusting 90 balancing weight —45—.

The thermostatic device is rigidly supported by means of a bracket —46— connected to the heater —1— and supporting a tubular member —47—, which in turn 100 supports a horizontal bracket —48— upon which the arm —42— is pivotally mounted.

The opening —37— connecting the chamber —33— with the hover is normally partially closed by a lid —49— having an opening —50— through which the link —40— extends, and this opening is of sufficient size to provide a ventilating means for the hover operating in connection with the heat-controlling means and the smoke pipe —35—.

110

The operation of this portion of the device is as follows: The suction through the smoke pipe or chimney —35— is constant and when the valve —38— is in closed position, chimney or smoke pipe draws from 115 the hover and the room. When the valve —38— is partially open, the chimney draws partially from the fire-box of the heater —1— and partially from the hover, and when the valve —38— is entirely open, it 120 closes the opening —50— and the chimney draws entirely from the fire-box of the heater, thereby constituting a combined draft regulator and ventilator.

125 The thermostatic device may be set to operate at any predetermined temperature by the weight —45— and as the temperature increases in the hover the bellows —41— will expand and actuate the lever —42— to draw the rod —43— downwardly and there- 130

by close the valve —38—. As the temperature decreases, the weight —45— will return the valve to open position as limited by the expansion of the bellows —41—.

5 The members —41—, —42—, —43—, —44— and —48— are preferably inclosed by a suitable screen —51— to prevent the fowls from coming in contact with these members to prevent accurate operation of 10 the same, and to prevent the deposit of litter and other foreign matter which would decrease the exactness of operation.

What I claim is:—

1. In a brooder, a cylindrical shell open 15 at one end and a heater disposed substantially centrally of said shell, said cylindrical shell having a movable sector shaped section hinged eccentrically of the shell.
2. In a brooder, a cylindrical shell open

at one end, a heater disposed substantially 20 centrally of said shell, said shell having a movable sector shaped section hinged eccentrically of the shell at two separate points disposed vertically above each other, one of said hinging points being off-center from the 25 other.

3. In a brooder, a cylindrical shell open at one end, a heater disposed substantially 30 centrally of said shell, said shell having a movable sector shaped section hinged eccentrically of the shell and means for tilting said section as it is moved to open position.

In witness whereof I have hereunto set my hand this 30th day of September, 1914.

WILLIS A. SCHLEIT.
